UNITED STATES PATENT OFFICE.

ALEXANDER DICKEY, OF HONEYVILLE, UTAH.

RIFLE SIGHT.

1,425,756.

Specification of Letters Patent. Patented Aug. 15, 1922.

Application filed February 13, 1922. Serial No. 536,174.

To all whom it may concern:

Be it known that I, ALEXANDER DICKEY, a citizen of the United States, residing at Honeyville, in the county of Boxelder and 5 State of Utah, have invented a new and useful Rifle Sight, of which the following is a specification.

This invention relates to sights for fire arms, and more particularly to sights of the 10 adjustable type, the primary object of the invention being to provide means to adjust the inner sight, or opening of the inner sight through which the outer sight is observed.

Another object of the invention is to provide means for adapting a fire arm for long 15 or short range firing.

A still further object of the invention is to provide a device of this character which may be readily and easily applied to fire arms 20 now in use, eliminating the necessity of making alterations in the usual construction to apply the device.

With the foregoing and other objects in view which will appear as the description 25 proceeds, the invention resides in the combination and arrangement of parts and in the details of construction hereinafter described and claimed, it being understood that changes in the precise embodiment of the invention herein disclosed, may be made within 30 the scope of what is claimed, without departing from the spirit of the invention.

Referring to the drawing:—

Figure 1 is a fragmental elevational view 35 of a fire arm barrel, disclosing a sight constructed in accordance with the present invention as applied thereto.

Figure 2 is an elevational view of the same.

Figure 3 is a sectional view taken on line 40 3—3 of Figure 2.

Figure 4 is a sectional view taken on line 4—4 of Figure 1.

Figure 5 is a sectional view taken on line 45 5—5 of Figure 2.

Referring to the drawing in detail, the sight includes a body portion 5 formed with lateral extensions 6, which extensions are positioned in suitable grooves formed in the 50 barrel, which in the present showing is indicated at 7.

The body portion 5 is relatively long, and is formed with a head 8, disposed at one end thereof, which head is provided with a V-shaped cut away portion 9 through which 55 the usual stationary sight at the outer end

of a barrel of a fire arm, is observed. The head is also formed with a groove 11 formed transversely thereof, which groove provides a guideway for the laterally adjustable sight 60 members 12, which are formed with threaded openings to accommodate the threaded ends 13 of the adjusting screw 14, the threads at the ends of the adjusting screw being oppositely formed so that rotation of the adjusting screw will cause the members 12 to move with respect to each other, to vary the distance between the members 12, to regulate the sight opening.

In order that the adjusting screw 14 will 70 be held against lateral movement, shoulders 15 embrace opposite sides of the block 16 disposed at the base of the groove 11. Associated with the sight members 12 is a vertically adjustable sight member 17 which is 75 formed with ribs 18 moving in suitable grooves formed in the head 8. This sight member 17 is also formed with a V-shaped groove 19 adapted to align with the cut out portion of the head and space between the 80 sight members 12, providing an opening to permit the gun to be properly sighted.

A set screw 20 is carried by the sight member 17 so that the sight member may be secured in various positions of vertical adjustment. Supported under the body portion of the sight, is an adjustable member 21 which is formed with upwardly extending side walls 22, the upper edges thereof being inclined towards the head of the sight 90 proper. Notches 23 are formed along the upper edges of the walls, which notches accommodate the shoulders 24 formed at the base of the head. From the foregoing it will be obvious that by moving the member 95 21 longitudinally of the body portion of the sight proper to bring the shoulders 24 into certain notched portions, the body portion of the sight proper may be adjusted with respect to the barrel 7, supporting the same. 100

In order that the adjusting member 21 may be moved, a finger piece 25 is formed at the outer end thereof, to allow the operator to grip the same. In view of the foregoing description, it is believed that further detail description as to the operation of the device is unnecessary.

Having thus described the invention, what is claimed as new is:—

1. In a sight for fire arms, a body portion 110 having a head formed at one end thereof, said head having a cut out portion and hav-

ing a groove formed transversely thereof, laterally adjustable sight members disposed within the groove, a vertically adjustable sight member associated with the laterally 5 adjustable sight members, and an adjustable member disposed under the body portion.

2. In a sight for fire arms, comprising a body portion, a head formed at one end of the body portion, said head having a laterally 10 extending groove, sight members supported within the groove, said sight members adapted to move towards and away from each other, a vertically adjustable sight member associated with the first mentioned sight members, and means movable 15 under the body portion for adjusting the body portion vertically.

3. In a sight for fire arms, a body portion, a head formed integral with the body portion at one end thereof, said head having a 20

groove, sight members positioned in the groove, each of said sight members having a threaded opening, an adjusting screw having its ends disposed within the threaded openings of the sight members, the threads 25 of the adjusting screw being formed in opposite directions to move the sight members with respect to each other, a vertically adjustable sight member associated with the first mentioned sight members, and adjustable means disposed under the body portion for moving the body portion vertically.

In testimony that I claim the foregoing as my own, I have hereto affixed my signature in the presence of two witnesses.

ALEXANDER DICKEY.

Witnesses:

JAMES S. HUNSAKER,
NEWMAN HUNSAKER.
